POUR CONTAINER

Marian C. Falk, Boise, Idaho

Application February 15, 1949, Serial No. 76,522

2 Claims. (Cl. 229—17)

1

This invention relates to a pour container, and more particularly, to a non-drip pour container and to a type of container which may be shipped or transported in stacked relation with similar sealed containers carrying fluid contents such as liquids, cereal, or other particulate materials that flow. The invention is particularly useful in connection with the packaging of milk, cream and other liquid.

An object of the invention is to provide a container so arranged as to provide a tight seal for the transportation of liquids or particulate flowing materials, while being readily opened to provide a pouring spout or channel, while eliminating dripping.

Yet another object is to provide a container adapted to be sealed in a square or other form the top of the container being arranged for opening to expose folded portions providing a pour spout, etc.

Other objects and advantages will appear as the specification proceeds:

The invention is illustrated in preferred embodiments by the attached drawings in which—

Figure 1 is a perspective view of a container embodying my invention;

Figure 2, a view similar to Fig. 1, but showing the top flap raised;

Figure 3, a perspective view of the container turned to pouring position;

Figure 4, a broken detailed sectional view, the section being taken as indicated by line 4—4 of Fig. 1;

Figure 5, a broken detailed sectional view, the section being taken as indicated at line 5 of Fig. 1;

Fig. 6, a top plan view of the die-cut sheet from which the container is formed;

Figure 7, a vertical section view, the section being taken as indicated at line 7—7 of Fig. 1;

Figure 8, a broken sectional view similar to Fig. 7, but showing a modified form of structure.

In the illustration given a flat strip of paper is die-cut, as shown in Fig. 6 and preferably indented to form fold lines. The other lines are indicated by solid lines in Fig. 6, while the folded lines are indicated by the dotted lines 10. The side walls of the container are formed by the sides 11, 12, 13 and 14 as indicated in Fig. 6 and the flaps 15 and 16 are provided for reinforcing the sealing joint. The lower flaps 17, 18, 19 and 20 are folded to form the bottom of the container, as in usual practice.

The top flap 21 serves an important function in providing a seal for the top of the container.

This flap is provided at one end with a cut-out or aperture 22 to permit the flow of liquid therethrough. The flap 23 forms the top or outside seal for the container. The flap 24 is adapted to be folded inwardly at an intermediate point and above the adjacent flap 25. The adjacent flap 25 is folded upon itself at the fold line 26. As will be later described, the flaps 25 and 24 cooperate in forming the spout for the pouring of the milk, etc. and the bottom of the channel of the spout is the folded line 27.

I prefer to equip the flap 16 with an upper extension 28 in order that this pull flap 28 may be utilized in the opening of the container top.

The container may be folded and united by glue, wax or by any other sealing means. The container itself may be formed of paper rendered waterproof by plastic materials, waxes or any other well known means or it may be formed of other flexible material such as plastic sheets, etc.

The flat sheet, as shown in Fig. 6 is folded upon itself as illustrated in Figs. 1 to 5 and 7 inclusive so as to form a square container and the finished sealed container appears as shown in Fig. 1. I prefer to have the flap 23 provided with an extension 29 and with a pour pull flap 30, as shown more clearly in Figs. 1 and 6.

The finished container may be left with the flaps 21, 23, 24, 25 and 28 extended for the filling operation and thereafter the flaps may be folded inwardly, first the flap 21 being brought into sealing position within the container. Next the flap 25 is folded into position, the flap 25 being folded upon itself. The outer flap 23 forms the closure for the container and the overlapped portion 29 provides a reinforced front edge. The top portion or tab 28 provides a seal which at the same time can be readily pulled to open the container. If desired, flaps 29 and 30 may be omitted or may be varied in shape as desired for sealing. The flap 29 may be slit to improve the seal.

When it is desired to open the container for pouring the milk or other liquid, the flap 30 is grasped and drawn upwardly as shown in Fig. 2. The flap 24 is then drawn forwardly to the position shown in Fig. 3 for pouring. This causes the channel portion formed by the two flaps 24 and 25 as shown in Fig. 3, to be aligned with the aperture provided in the corner of the flap 21 so that liquid or flowable particulate materials may flow readily from the container and through the spout which may be indicated as an entirety by the numeral 32 as shown in Fig. 3.

In the modification shown in Fig. 8, the struc-

ture is identical as that heretofore described except that I have provided the lowermost flap within the container, namely, flap 21a with attachment flanges 21b and the attachment flanges are preferably cemented to the side walls of the container, thus providing a rigid sealing wall 21a fixed firmly to the interior walls of the container and providing a single outlet 33.

The invention has been described by way of example, in connection with a container for milk. In the case of materials such as sugar, materials and other materials consisting of small flowable solids, it may be desirable to vary the size or shape of the aperture 22 in flap 21.

While in the foregoing specification, I have set forth a specific structure in much detail for the purpose of illustrating one embodiment of my invention, it will be understood that such details of structure may be varied widely by those skilled in the art without departing from the spirit of my invention.

I claim:

1. A container formed from a flat strip folded upon itself to form an enclosure with overlapping top flaps and side walls connected thereto, one of said top flaps fitting tightly the container interior to form a closure and having a portion thereof cut away to form a pour opening, another of said top flaps being folded for forming, when raised, a channel aligned with said pour opening, a third top flap member enclosing said first-mentioned top flap and having a depending tab extending downwardly along one side wall of the container and adjacent one edge of the side wall, said container having a front flap opposite the side wall connected to said third top flap, and

a pull flap integral with said front flap of said container, extendable and foldable over said third top flap and over said first-mentioned flap and adapted to be secured to said third top flap.

2. A container formed from a flat strip folded upon itself to form an enclosure with overlapping top flaps and side walls connected thereto, one of said top flaps fitting tightly the container interior to form a closure and having a corner portion thereof cut away to form a pour opening, another of said top flaps being folded intermediate its width to form, when raised, a channel aligned with said pour opening, a third top flap enclosing said first-mentioned top flap and having a depending tab extending downwardly along one side wall of the container and adjacent one edge of the side wall, said container having a front flap opposite the side wall connected to said third top flap, and a pull flap integral with said front flap of said container, extendable and foldable over said third top flap and over said first-mentioned flap and adapted to be secured to said third top flap.

MARIAN C. FALK.
